UNITED STATES PATENT OFFICE.

SHOJIRO SHIBAMURA, OF TOKYO, JAPAN.

PAGE-TURNER.

1,367,101.

Specification of Letters Patent.

Patented Feb. 1, 1921.

Application filed April 20, 1918. Serial No. 229,842.

To all whom it may concern:

Be it known that I, SHOJIRO SHIBAMURA, musician, a subject of the Emperor of Japan, residing at No. 60 Sakurada-Machi, Azabu-Ku, city of Tokyo, Japan, have invented certain new and useful Improvements in Page-Turners, of which the following is a specification.

This invention relates to music leaf or page turners and more particularly to that class of devices adapted for use in mechanically turning the sheets of music so as to leave the hands of the performer free for playing, and it has for its object to provide a device of this character whereby the music can be readily turned in either direction, according to the requirements, by means operable by the foot or the knee of the performer.

20 A further object of the invention is to provide a device of this character which will prevent the leaves being forced out of position by a draft or from any other cause.

25 A further object of the invention is to provide a device which can be readily applied to a piano, or to a tripod or any usual kind of music stand, and generally to provide a device of the kind referred to which will be efficient, simple in construction and inexpensive to manufacture.

30 With the above and other objects in view, which will be apparent from the following description, my invention consists in the novel structures, arrangements and combinations of parts to be described with reference to the accompanying drawings and more particularly set forth in the appended claims.

35 In the drawings:

40 Figures 1^a to 1^e illustrate a complete device embodying my invention, Fig. 1^a being a perspective view of the device ready to be operated, Fig. 1^b a rear view of the device in inoperative position, Fig. 1^c a top view of same, Fig. 1^d a perspective view of the locking mechanism and Fig. 1^e a view of the device mounted on a piano;

45 Figs. 2^a to 2^f illustrates the principal parts of my device in detail, Fig. 2^a being a perspective view of the pivoted inner end of a page turning arm with its spring, Fig. 2^b a fragmentary view of the base of the device with page turning arms pivoted thereto, Fig. 2^c illustrating a page turning finger, Fig. 2^d a telescopic rod forming part of the actuating mechanism, Fig. 2^e showing the locking

mechanism and the locking member separately, and Fig. 2^f being a plan view of the locking mechanism in operative position;

5 Figs. 3^a to 3^d illustrate a modification of my invention in which the page turning fingers are adapted to grip the leaves or pages to be turned, Fig. 3^a being a perspective view of the device ready for use, Fig. 3^b illustrating a gripping finger and a clamp used for turning the pages in reverse direction, Fig. 3^c an arm used for reversing the movement of the pages, and Fig. 3^d being an enlarged view illustrating the reversing mechanism;

60 Figs. 4^a and 4^b illustrate the invention applied to a music stand, 4^a showing the complete device and Fig. 4^b a portion of the actuating connections on an enlarged scale.

65 Referring to Figs. 1^a and 1^b, reference numeral 5 designates the base of my leaf 70 turner which rests on adjustable brackets 4 adapted to be secured to the upper edge of a suitable support such as a backboard 6. To the base 5 is secured a substantially vertical pin or shaft 7 to which are pivoted a series 75 of horizontal arms 8, each of which is normally held in the inoperative position shown in Fig. 1^b by a coil spring 3, one end of which bears on a projection 9 rising from the base and the other on the inner end 10 of the 80 arm 8 controlled by said spring. The projection 9 and the pivoted arm portions 10 herein shown have been given similar fanciful shapes for purposes of ornamentation. When the arms 8 are moved to the left in 85 Fig. 1^b (or from left to right in Fig. 1^a) about their pivot 7, they are engaged by a locking mechanism comprising a channel shaped trap 11 integral with or secured to the base 5 and a fork shaped locking member 12 mounted to oscillate on a horizontal pivot 13 carried by the frame 11.

90 The locking member or rocker 12 comprises an arcuate portion having tapered ends 14 and 15 and a short vertical arm 16 100 so arranged that when said arm is pulled laterally, as by a wire 17, the locking member will swing about its axis 13 against the tension of a spring 18 which acts to return the member 12 to its normal position when 105 the wire 17 is released. The ends 14 and 15 of the locking member extend through slots 19 and 20 respectively in the frame 11, as best shown in Fig. 2^e, and they are adapted to latch the arms 8 under tension when the 110 device is set. The latch 14 has an inclined front surface 21 so arranged that when the

arms 8 are forced into the frame or trap 11 against the tension of their springs 3 the member 12 yields to their movement, but when they are released within the trap they 5 are retained therein by said locking member. As shown in Figs. 2^a and 2^f, latch 15 is offset with respect to latch 14 to an extent corresponding to the thickness of one arm 8. The arms 8 are kept a short distance apart 10 by distance pieces 22 secured thereto (Fig. 2^f).

The number of arms 8 will vary according to the requirements, there being five such arms in the example illustrated. Secured 15 to the free outer end of each arm 8 is a depending finger 23 provided with a page engaging roller 24 (Fig. 2^a) which may have a roughened or knurled surface and, preferably, is surrounded with a rubber sleeve 25.

20 To the arm 16 of the locking member 12 is secured a wire or cord 17 attached to the end of a crank 30 secured to an extensible rock shaft (Fig. 2^a). This shaft comprises a polygonal section 31 and a tubular section 25 32 having a polygonal bore 33 adapted to receive the polygonal section 31. The tubular section 32 fits in a guiding sleeve 34 which is provided with lugs 35 whereby it can be secured to the backboard 6. Secured to the section 32 is a crank 36 which is connected by means of a wire or cord 37 to an actuating spring lever 38 (Figs. 1^a and 1^e) adapted to be secured beneath the keyboard of the piano. It will be understood 30 that when lever 38 is depressed with the knee, the shaft 31, 32 will be rocked and the wire 17 caused to swing the locking member 12 about its pivot 13, thus lifting the latch 14; also that the shaft 31, 32 will 40 accommodate itself to any adjustment in the height of the backboard 6 which is herein shown to be formed of two parts, the top part being adjustable in a well known manner.

45 The modified structure illustrated in Figs. 3^a to 3^d is generally similar to that shown in Figs. 1^a to 2^f in so far as the parts described above are concerned, with the exception of the page engaging fingers which, 50 in Figs. 3^a to 3^d, comprise clips 26 adapted to grip the pages to insure a permanent control of the music by the turning device.

In operation the fingers 23 or 26 are caused to engage the pages to be turned and the 55 arms 8 are successively introduced into the trap 11 where they are held by the locking member 12, as explained before. When it is desired to turn a page the lever 38 is depressed with the knee to raise the latch 14 60 and liberate the foremost arm 8 which is then free to swing about its pivot 7 under the action of its spring 3 and carries the music leaf or page with it. As the latch 14 is raised the latch 15 is depressed and thus 65 prevents the next arm 8 following the arm

just freed. The member 12 then swings back to its initial position under the influence of spring 18 and the latch 15 is withdrawn from the path of the next arm 8 which moves into engagement with the latch 14 70 and is now ready to turn the next page when the lever 38 will again be actuated.

Means are also provided for reversing the movement of the pages when it is desired to repeat a composition. In the embodiment 75 shown in Figs. 1^a to 2^f, such means comprise an arm 40 pivoted at 41 to a support 42 carried by the backboard 6, and normally held in the position shown in Figs. 1^a and 1^b by means of a coil spring 43 similar to 80 the springs 3. The arm 40 carries a depending finger 44 with rubber sleeve 45 similar to the fingers 23 and sleeves 45 respectively.

The arm 40, when swung to the left (Fig. 85 1^a) about its pivot 41, is adapted to enter the trap 11 where it is held against the tension of its spring 43 by the locking member 12 (Fig. 1^d). The music to be repeated is engaged on one side by the finger 44 and on the other side by two fingers 23, the arm 40 being interposed between the arms 8 to which the said fingers 23 are secured. By operating the actuating lever three times in succession the foremost arm 8 is first released 90 to turn the leaf, then the arm 40 is caused to restore it to its initial position and finally the second arm 8 repeats the movement of the first arm 8. It is obvious that a plurality of arms 40 may be mounted on the pivot 41 if desired. As shown in Fig. 1^a, the finger 44 swings clear of the music as it approaches its normal inoperative position.

In the modification illustrated in Figs. 3^a to 3^d the reversing arm 50 is pivoted to an extension 51 of the pin 7 on which the arms 8 are pivotally mounted. It is normally held in the position shown in Fig. 3^a by a spring 53 (Fig. 3^e) which is more powerful than the springs 3 for actuating the arms 110 8. The arm 50 carries no page engaging finger, but it can be secured to any of the arms 8 by means of a clamp 52 (Figs. 3^b and 3^d). To lock the arm 50 in the position shown in Fig. 3^d I provide a hook 54 on 115 one end of a lever 55 centrally pivoted to the base 5 and connected at its other end to a wire 56 adapted to be operated by means of a lever (not shown) similar to the lever 38 in order to release the arm 50. 120 The arm 50 is preferably provided with a hinged end portion 57 which, when the said arm is returned to its normal position abuts against a tripping member 58 adapted to be operated by the connections 56 and 59 125 to disengage the arm portion 57 from the clamp 52 and liberate the arm 8.

Figs. 4^a and 4^b show my improved device mounted on a music stand. The base 5 is supported by a bracket 60 adjustably se- 130

cured to the stand 61 by a screw 62. The locking member or rocker 12 is operated by means of a resilient pedal 63 through a connection comprising wire 64, bell-crank lever 5 65 and wire 66.

It will be obvious that many changes may be made in the construction and arrangement of the embodiments described without departing from the scope of my invention 10 as set forth in the appended claims.

I claim:

1. In a page turning device, a base, a pin on said base, a plurality of spring controlled arms pivotally mounted on said pin, and 15 means for holding said arms against the tension of their respective springs, said means comprising a channel shaped trap adapted to receive said arms, a rocking member mounted on said trap, latches on the ends of 20 said member, said latches being adapted to extend through slots in a wall of the trap into the path of the arms and one of said latches being offset with respect to the other, and a spring normally holding one of said 25 latches within said trap.

2. In a page turning device, a base, a pin on said base, a plurality of spring controlled arms pivotally mounted on said pin, and means for holding said arms against the 30 tension of their respective springs, said means comprising a channel shaped trap on said base, a fork shaped rocker on said trap, and latches on the ends of the two fork arms, said latches being adapted to extend through 35 slots in a wall of the trap into the path of the arms and one of said latches being offset with respect to the other, the front face of one of said latches being inclined, and means for actuating said rocker.

3. In a page turning device, a base, a pin on said base, a plurality of spring-controlled arms pivotally mounted on said pin, means for latching said arms under tension including a rocker and latches connected with said 45 rocker and adapted alternatively to engage and release said arms in succession upon operation of said rocker, and means for actuating said rocker including an extensible rockshaft.

4. In a page turning device, a base, a pin on said base, a plurality of spring-controlled arms pivotally mounted on said pin, means for latching said arms under tension including a rocker and latches on said rocker, said 55 latches being offset with respect to one another, a rockshaft comprising a polygonal section and a tubular section having a polygonal bore adapted to engage said polygonal

section, an operating lever, a crank on each of said shaft sections, a flexible connection 60 between said rocker and one of said cranks, and a flexible connection between said actuating lever and the other of said cranks.

5. In a page turning device, spring-controlled means adapted to turn the pages 65 in one direction, spring-controlled means adapted to turn the pages in the opposite direction, and means for latching both said means under tension, said latching means including a rocker and a pair of latches connected with said rocker, said latches being offset with respect to one another and adapted to release one of said means at a time.

6. In a page turning device, a plurality of 70 pivotal arms, springs tending to move some of said arms in one direction, a spring tending to move one of said arms in the opposite direction, and means for controlling the movements of said arms, said means including a rocker and a pair of latches connected with said rocker and offset with respect to one another.

7. In a page turning device, a plurality 75 of pivotal arms, page engaging fingers on said arms, springs tending to move some of said arms in one direction, a spring tending to move one of said arms in an opposite direction, and latching means adapted to engage each and all of said arms and hold 80 them against the tension of their respective springs, said latching means including a rocker and a pair of latches connected with said rocker, said latches being offset with respect to one another and adapted to release one of said arms at a time.

8. In a page turning device, two substantially parallel pins, a plurality of spring-controlled arms pivotally mounted on one of said pins, a spring-controlled arm pivotally mounted on the other pin, latching means adapted to hold said arms under tension including a rocker and a pair of latches offset with respect to one another carried by said rocker, and means for actuating said 105 rocker, including an extensible crank shaft, flexible connections and an actuating lever within the reach of the operator's foot or knee.

In testimony whereof I affix my signature 110 in presence of two witnesses.

SHOJIRO SHIBAMURA.

Witnesses:

H. F. HAWLEY,
S. HORIYE.
